UNITED STATES PATENT OFFICE.

JOHN JENKINS, OF DALMUIR, SCOTLAND.

VENTILATOR-COWL FOR SHIPS.

1,228,677.

Specification of Letters Patent.

Patented June 5, 1917.

Application filed October 10, 1916. Serial No. 124,754.

To all whom it may concern:

Be it known that I, JOHN JENKINS, a subject of the King of Great Britain, residing at Dalmuir, in the county of Dumbarton, 5 Scotland, have invented certain new and useful Improvements in Ventilator-Cowls for Ships, of which the following is a specification.

My invention relates to improvements in 10 ventilator cowls for ships and particularly has for its object the providing of a simple down-draft ventilator or improved means for preventing the ingress of water to the ventilating trunk upon which the cowl is 15 arranged and adapted to be fitted.

In the drawings forming a part of this specification and in which the same reference characters are employed throughout the various views to designate the same parts, 20 Figure 1 is a central vertical section of my improved ventilator cowl; Fig. 2 is a front elevational view; Fig. 3 is a horizontal section taken on the line 3—3 of Fig. 1; and Fig. 4 is a horizontal section taken on the 25 line 4—4 of Fig. 1.

As shown in the drawings, a ventilator cowl made in accordance with this invention comprises essentially two coaxial substantially cylindrical structures or members A¹, 30 being rotatable relatively to the outer one A on a pivot A² in the upper closed ends of the structure or members A, A¹. The whole cowl, comprising the members A, A¹, is rotatably mounted in the usual manner upon 35 a suitable ventilating trunk (not shown) and the two structures or members A, A¹ are preferably connected together by stays B, B¹ hinged at their upper ends to the outer structure A and removably attached at their 40 lower ends to the inner structure A¹. In the inner and outer structures or members A, A¹ are provided segmental apertures C, C¹, that is to say, apertures which are rectangular in shape with their longer sides substantially parallel with the axis of the structures or members A, A¹.

The member A may be rotated with respect to the member A¹ so that both apertures C, C¹ face in the direction of the wind, 50 but when the possible ingress of water is to be prevented, the stays B, B¹ are disconnected and the structure or member A is rotated with respect to the structure A¹ so that the apertures C, C¹ are set diametrically 55 opposite to one another, in which position they are shown in Figs. 1, 2 and 3 of the

drawings. The apertures C, C¹ may be provided with louvers.

In the annular segmental space between the cylindrical structures A, A¹ are arranged 60 lip-like baffles D extending inwardly from the outer structure A and outwardly from the inner structure A¹ and they are arranged in a staggered position with respect to each other so as to cause the ingoing, spray-laden 65 air to be deflected over and around them. Two other baffles D¹, D² are also carried by the outer structure or member A so that they lie in the center of the annular space between the members A, A¹, one on each side 70 of the aperture C¹ in the inner structure or member A¹ when the parts are in the position shown in Figs. 1 and 3.

In the open annular space between the lower edge or skirt of the outer member or 75 structure A and the outer surface of the inner structure A¹ are arranged series of annular louvers E, E¹ oppositely angled, which, while they permit of the draining out 80 of any water in the space between said members, prevent the entry of spray with which ingoing air may be laden. To further assist in preventing the upward 85 passage of water above the louvers E, E¹ the inner structure A¹ carries at the lower edge 90 of the aperture C therein a series of louvers G overlapping each other. At a little distance from the inner surface of the outer structure A and opposite the aperture C¹ in the inner structure A¹ when the latter is 95 in the position shown in Figs. 1 and 3, is supported a perforated plate G¹. This plate G¹ carries on its face, which is adjacent the inner member A¹, a series of oppositely angled vertical baffles G².

Vertical lips H are provided at the vertical edges of the aperture C¹ in the inner structure A¹, and at the lower edge of this aperture C¹ is a well H¹ communicating by way of an aperture or passage H² with the 100 outside of the inner structure A¹, below the skirt of the outer structure A. In the well H¹ is also provided a lipped aperture or air passage J communicating with the interior of the inner structure A¹.

By the above arrangement, the air entering or admitted to the interior of the inner structure A¹ either through the openings C in the outer structure A or through the open annular space between the outer 110 edge or skirt of the outer structure or the outer surface of the inner structure A¹, is

subjected to the action of baffle plates which prevent the ingress of water into the interior of the inner member or structure A^1 , and that the water or spray which may collect 5 upon the interior of the outer structure A or the exterior of the inner structure A^1 or the baffle plates provided as above set forth within the space between the inner and outer members or structures A , A^1 , is free to drop 10 out of the space between the inner and outer members A , A^1 outside of the inner member A^1 and any moisture which collects at and falls from this surface of the inner member A^1 adjacent the opening C^1 collects in the 15 well H^1 from which it is conducted through the passage H^2 to the outside of the inner member A^1 .

Having thus described my invention I claim and desire to protect by Letters Patent 20 of the United States:

1. In a ventilator cowl for ships, the combination of two coaxial substantially cylindrical structures or members one within the other and each provided with a segmental aperture respectively, baffles on said structures extending into the space between them, louvers in the lower open end of the space between said structures and a well at the lower edge of the aperture in the inner 30 of said structures, said well being provided at its bottom with apertures communicating with both the inside and the outside of said inner structure.

2. In a ventilator cowl for ships, the combination of two coaxial substantially cylindrical structures one within the other and each provided with a segmental aperture respectively, baffles on said structures extending into the space between them, louvers in the lower open end of the space between said structures, and a well at the lower edge of the aperture in the inner structure, said well being provided with apertures communicating with the outside 40 of said inner structures and with an air passage a little above the bottom of said well and communicating with the interior of said inner structure.

3. In a ventilator cowl for ships, the combination of two coaxial substantially cylindrical structures one within the other and each provided with a segmental aperture respectively, said apertures being on opposite sides of the axis of said structures, a 50 perforated plate extending in the space between said structures and arranged between the inner surface of the outer structure and the said aperture in the inner structure and oppositely angled, vertical baffles extending from that face of said perforated plate which is adjacent said aperture in said inner structure.

4. In a ventilator cowl for ships, the com-

bination of two coaxial substantially cylindrical structures one within the other and 65 each provided with a segmental aperture respectively, two series of angular louvers oppositely angled with respect to each other and positioned within the lower end of the outer structure in the space between said 70 structures and a further series of overlapping louvers above the said series of angular louvers, mounted on said inner member at substantially the lower edge of the aperture in said inner member. 75

5. In a ventilator cowl for ships, the combination of an outer cylindrical member provided with an aperture in the side thereof, an inner cylindrical member mounted coaxially with said outer member and also 80 provided with a similar aperture through the side thereof, the space between said members affording a passage for air between said members to the opening in said inner member, vertically extending baffle plates 85 in the inner surface of the outer member and the outer surface of the inner member, louvers between the said inner and outer members positioned at the lower end of said outer member, and a series of louvers secured to said inner member adjacent the bottom edge of the said aperture therein and extending substantially between said inner and outer members. 90

6. In a ventilator cowl for ships, the combination of an outer cylindrical member provided with an aperture in the side thereof, an inner cylindrical member mounted coaxially with said outer member and also 100 provided with a similar aperture through the side thereof, the space between said members affording a passage for air between said members to the opening in said inner member, vertically extending baffle plates 105 in the inner surface of the outer member and the outer surface of said inner member, louvers between the said inner and outer members positioned at the lower end of said outer member, a series of louvers secured to said inner member adjacent the bottom edge of the said aperture therein 110 and extending substantially between said inner and outer members, an air passage extending between the space between said members and the interior of said inner member downwardly from a point adjacent the lower edge of the opening in said inner member to a point below the lower edge of said outer member and means to collect moisture in said passage and discharge it 115 outside of said inner member. 120

In witness whereof I have hereunto set my hand this 22nd day of September, A. D. 1916.

JOHN JENKINS.
